UNITED STATES PATENT OFFICE.

HARLEY E. ANDERSON, OF CHICAGO, ILLINOIS, ASSIGNOR, BY MESNE ASSIGNMENTS,
TO W. H. MINER, INC., A CORPORATION OF DELAWARE.

RAIL ANCHOR.

Application filed October 9, 1922. Serial No. 593,458.

To all whom it may concern:

Be it known that I, HARLEY E. ANDERSON, a citizen of the United States, residing at Chicago, in the county of Cook and State 5 of Illinois, have invented a certain new and useful Improvement in Rail Anchors, of which the following is a full, clear, concise, and exact description, reference being had to the accompanying drawings, forming a part 10 of this specification.

This invention relates to improvements in rail anchors.

The object of my invention is to provide an efficient rail anchor of simple construction which operates to tightly clamp the rail and positively prevent relative creeping of the rail and tie.

A still further and more specific object of my invention is to provide a rail anchor 20 composed of three members, so arranged as to tightly interlock and positively clamp the rail. Other objects of the invention will more clearly appear from the description hereinafter following.

25 In the drawing forming a part of this specification, Figure 1 is a vertical sectional view through a rail, showing applied thereto, in elevation, a rail anchor embodying my improvements. Figure 2 is a side elevation 30 looking from the left in Figure 1, showing a tie in section and illustrating the relative position of the tie, rail anchor and rail. Figure 3 is a sectional view taken substantially on the line 3—3 of Figure 1. Figure 35 4 is a perspective view of the combined hook and wedge member. And Figure 5 is a perspective view of the heel block.

In said drawing, 10 indicates a rail of the usual type comprising a rail head 11, 40 a vertically extending web 12 and a base member 13 having my improved rail anchor clamped thereto.

45 My improved rail anchor comprises, broadly, a cross piece A, a wedge B and a heel block C. The cross piece A consists of a horizontal bar portion 14 having angularly projecting flanges 14', said cross piece contacting with the lower face of the rail base 13 and having a hooked member 15 at one 50 end engaging the upper surface and the outer edge of the rail base. The opposite end of the cross piece A is provided with a recess 16 extending therethrough, said recess

having a downwardly inclined wall 17 adapted to coact with the wedge B.

55 The wedge B is of angular construction comprising an upper engaging jaw 18 and a downwardly tapering shank 19 coacting with the inclined wall 17 of the cross piece A. As is clearly shown in Figure 4, the wedge B is provided with opposite reinforcing flanges 20—20 and the lower end of the shank 19 of the same has wedge lugs 21—21 extending laterally therefrom on opposite sides. The said wedge lugs 21 are provided 65 with inclined upper faces 22 extended oppositely from the center of said lugs.

The said block C is of generally rectangular outline, having a flat face 23 adapted to engage with the tie and having the face opposite said face 23 cut away, as shown at 70 24. A T-shaped slot 25 is provided in the upper side of the heel block C adapted to receive the lugs 21 of the wedge, the upper longitudinal walls of the slot coacting with 75 the wedge faces 22 to pull the wedge B downwardly, thereby forcing the jaw 18 into intimate contact with the rail base and pulling the hook 15 toward the wedge B.

80 In applying my improved rail anchor to a rail, the hook end 15 of the cross piece A is first engaged with one edge of the rail base. The wedge B is then forcibly driven into the opening 16, thereby forcing the hook 15 and the jaw 18 toward each other 85 due to the wedging action of the coacting faces of the wedge and the cross piece thereby tightly clamping the rail. The heel block C is then driven onto the lugs 21 at the lower end of the wedge B, and, due to 90 the camming or wedge action of the faces 22, the wedge B will be pulled downwardly through the recess 16, thus forcing the jaw 18 and the hook 15 more tightly against the rail base.

95 Although I have herein shown and described what I now consider the preferred manner of carrying out my invention, the same is merely illustrative and I contemplate all changes and modifications that 100 come within the scope of the claims appended hereto.

I claim:

1. In a rail anchor, the combination with two relatively movable members having rail 105 gripping means thereon; of a tie engaging

element, said members and element having cooperating wedge acting means thereon disposed transversely of the rail for forcing the rail gripping means into intimate contact 5 with the rail base.

2. In a rail anchor, the combination with a member having rail gripping means thereon; of a second member having rail gripping means thereon, said members being arranged 10 for relative movement, and a tie engaging element, said first and second named members having cooperating wedging means thereon effective to move the gripping means into clamping contact with the rail 15 base, and said second named member and element having cooperating wedge acting means thereon for forcing the gripping means into intimate contact with the rail base.
- 20 3. In a rail anchor, the combination with a member having a rail gripping means at one end; of a second member having a rail gripping means at one end, said first and second named members having cooperating vertically arranged wedge faces thereon, and said second named member having also arranged at the end opposite to the gripping means a horizontally arranged wedge face thereon, and a tie engaging block, having 25 means thereon coacting with said horizontally arranged wedge face for forcing the rail gripping means into intimate contact with the rail base.
- 30 4. In a rail anchor, the combination with relatively movable rail gripping members, one of said members having longitudinally and transversely extending wedge faces, said longitudinally extending wedge face coacting with the other gripping member to 35 force said members against the rail base; of a tie engaging element having means thereon coacting with said transversely extending wedge face for forcing the gripping elements into firm clamping engagement with 40 the rail base.
- 45 5. A rail anchor, comprising a cross piece having a rail engaging hook at one end and a tapering opening at the other end, a wedge member adapted to be forced into said opening, said wedge member having a rail engaging hook at one end and laterally projecting lugs at the other end, said lugs being provided with upper wedge faces, and a slotted heel block having flanges adapted 50 to extend over said lugs and engage said wedge faces, thereby forcing said hooked end of the wedge member toward said cross piece as the heel block is forced onto the lugs of said wedge member.
- 55 6. A rail anchor comprising a cross piece having rail engaging means at one end, a wedge member adapted to coact with the opposite end of said cross piece; said wedge member having rail engaging means at one 60 end, and a heel block having means thereon 65

coacting with the other end of said wedge member to force the rail engaging end toward the cross piece.

7. A rail anchor comprising a rail engaging member, a rail engaging wedge, and a 70 tie engaging element having means thereon coacting with the wedge to lock the rail engaging member and the wedge to a rail.

8. In combination with a rail, a rail anchor comprising a member having means at 75 one end engaging the upper and lower surfaces of the rail base, said member having a wedge face at the other end, a wedge element coacting with said wedge face, said wedge element having means at one end engaging the upper surface of said rail, and a wedge face at the other end, and a block having means thereon coacting with the wedge at the end of said element to move 80 said element relatively to said member as the block is forced into engagement with said element, thereby forcing the engaging of said element and member into intimate contact with said rail base.

9. In combination with a rail having a 90 base, a rail anchor comprising a member having a rail base engaging hook at one end, a wedge coacting with the opposite end of said member to force the hook into intimate contact with the rail base, said wedge also 95 having a rail base engaging hook at one end, and a block having means thereon coacting with the other end of the wedge to move the wedge relatively to said member to force both of said hooks into intimate contact 100 with said rail base.

10. In a rail anchor, the combination with a cross piece having a hook at one end and provided with a vertically extending tapered recess extending through the other end; of a hook element having a tapering shank adapted to engage within said recess and having its free end projecting beyond said cross piece; and a block having means thereon adapted to engage said projecting end to pull the said tapered shank through said recess, thereby forcing said hooks toward each other.

11. In a rail anchor, the combination with a cross piece having a rail base engaging hook at one end and provided with a vertically tapered recess extending therethrough at the other end, a wedge element having a tapering shank adapted to be received within said recess, said element having a lateral rail engaging projection at one end.

12. In a rail anchor, the combination with a cross piece having a rail engaging hook at one end and provided with a vertically extending tapering recess at the other end; a wedge element having a shank received within said recess and a rail base engaging jaw laterally projecting therefrom, and a heel block detachably connected with the free end of said wedge element.

13. In a rail anchor, the combination with a member having means for engaging one edge of a rail base; of a second member having means for engaging the opposite edge 5 of the rail base, said members being adapted to be assembled by relative movement in a direction perpendicular to the rail base and provided with co-operating means urging the same toward each other when assembled; 10 and a tie-engaging member having means thereon cooperable with one of said first named members arranged to urge the latter and said tie-engaging member in a direction vertically toward each other when assembled. 15
14. A rail anchor comprising three elements, two of said elements having portions thereof adapted to engage opposite edges of

the rail base and the third element being arranged to engage the tie, said two rail-engaging elements having cooperable means so arranged that, upon assembling the rail base is gripped in a direction transverse of the rail, and additional cooperating means on all three elements so arranged that, upon assembling of the tie-engaging element with the other elements, the rail-engaging elements grip the rail base in a vertical direction. 20 25

In witness that I claim the foregoing I have hereunto subscribed my name this 20th 30 day of Sept., 1922.
